UNITED STATES PATENT OFFICE.

WILLIAM F. KIESEL, JR., OF ALTOONA, PENNSYLVANIA.

CAR-TRUCK.

No. 800,921.

Specification of Letters Patent.

Patented Oct. 3, 1905.

Application filed July 11, 1905. Serial No. 269,144.

To all whom it may concern:

Be it known that I, WILLIAM F. KIESEL, Jr., a citizen of the United States, residing at Altoona, in the county of Blair and State of Pennsylvania, have invented certain new and useful 5 Improvements in Car-Trucks, of which the following is a specification.

This invention relates more particularly to improvements in four-wheel trucks for rail- 10 way-cars; and the objects of my improvements are, first, to provide a truck which will be adapted for use in connection with cars having deep center sills, where it is required to drop the center-plate to near the level of the axles; 15 second, to provide for greater flexibility of the spring - rigging by passing the bolster across the truck under the wheel-pieces and supporting it therefrom by stirrups without the use of a spring-plank, utilizing the wheel- 20 pieces as equalizers and arranging spring resistances for the bolster against both vertical and lateral motion; third, to provide a brake-rigging especially adapted for the truck, which, however, is made the subject of a sep- 25 arate application, and, finally, to provide an all-metal construction so arranged and built up as to accomplish a decrease in the weight of the truck, while maintaining full strength in all parts by the judicious location of hangers 30 and distribution of metal. I accomplish these objects by arranging and constructing the several parts of the truck in the manner illustrated in the accompanying drawings, in which—

35 Figure 1 represents a plan view of my improved four-wheel car-truck with the top portion of one of the wheel-pieces broken away to show the parts contained between the members thereof; Fig. 2, a side elevation of the 40 same with parts broken away for one-half the length of the truck to show the arrangement of the parts between the members of the wheel-pieces; Fig. 3, a central longitudinal vertical section of the truck; Fig. 4, an end 45 elevation thereof with parts broken away to show details of construction; Fig. 5, a transverse section on the line $x-x$ in Fig. 1; Fig. 6, a vertical section through one of the wheel-pieces and bolster-hangers on the line $y-y$ in 50 Fig. 2, drawn to a larger scale; and Figs. 7 and 8 details showing a hanger-gib and its support.

Like numerals designate like parts in the several views.

The center-plate 1 rests upon a bolster 2, 55 formed from a steel plate pressed into the shape of an inverted U, the crown of the bolster being flat and of considerable breadth and the length of the bolster being such as to carry its ends out beyond the wheel-pieces 3 60 at each side. These wheel-pieces consist of pairs of steel channels, the members of which are set apart with their flanged sides turned toward one another. The bolster at each end rests upon a nest of six elliptic springs 4. Said 65 springs rest in turn upon carriers 5, which are supported at each end by hangers 6, depending from supports between the members of the wheel-pieces. The bolster is, in effect, a spring-beam hung in stirrups at each side of the 70 truck. In order to properly support these stirrups, which must carry the weight of one-half the car, I rivet between the members of each wheel-piece a pair of horizontal channels 7, 75 the flanges of which are faced in opposite directions and riveted to the wheel-pieces just inside of their flanges. Upon the upper channels 7 are riveted the supporting-plates 8, upon which rest the gibs 9, from which the hangers 6 swing. These gibs are flat plates 80 passing through an eye at the top of the hangers, and they are provided on their top edges with a semicircular groove into which the convexed end of the hanger-eye is fitted. This permits the hangers to rock sidewise on their 85 supports, the gibs being held against movement on their supporting-plates 8 by having their bottom edges set into the ribbed sockets 10, formed on the top of said plates. The lower ends of the hangers are coupled to the 90 ends of the carriers by means of similar gibs 9, passed through eyes in the carriers and hangers in inverted position. (See Fig. 6.) By this arrangement the bolster 2 is allowed some lateral play with respect to the wheel- 95 pieces, and the necessary flexibility in the truck is attained.

Between the horizontal channels 7, below the gib-supports, are spacer plates or castings 11 in order that the downward pull of the hangers upon the upper channels may be transmitted to the under channels, combining the two together in support of the weight upon said hangers. Below these spacers 11 and held in place by the same rivets which hold the spacers and gib-supports in place are steel castings 12, which hang down below the wheel-pieces and are provided with vertical face-

plates 13, which constitute guides for the bolster to prevent longitudinal motion thereof with respect to the wheel-pieces. Reinforcing or wear plates 14 are riveted around the outside of the bolster between these guides and over the point where the elliptic springs are secured to the bolster. The gib-supports, spacers, and bolster-guides are vertically slotted to allow for the passage therethrough of the hangers and of a width to give room for the lateral rocking movements of the hangers.

The wheel-pieces are supported at each end upon spring-coils 15, which rest upon the axle-boxes, caps 16 being riveted between the members of the wheel-pieces to receive these equalizer-springs and the axle-boxes being guided in the pedestals 17. The upturned flanges of the pedestals at each side engage the outer faces of the members of the wheel-pieces between them, said members being thereby bound together and strongly braced at these points. The pedestals at the bottom are connected by pairs of tie-bars 18, running from one pedestal to the other on each side, with space left between the members of each pair of ties sufficient to permit a jack to be applied directly under the axle-boxes so that the boxes may be raised without disturbing the pedestal-ties for the removal of axle-bearings. There is also room between these pedestal-ties for the carriers 5, which support the elliptic springs, and under said carriers the ties are provided with safety-guards 19, intended to support the carriers in the event of the giving away of any of the carrier-supports.

The ends of the wheel-pieces are connected by depressed cross-braces 20, which are formed from pressed-steel plates of inverted-U-shaped cross-section bent up at each end and provided with flat portions 21, which are riveted to the under flanges of both members of the wheel-pieces. Brackets 22, of cast-steel, are riveted in the angles between the cross-pieces and the inside members of the wheel-pieces. The ends of the wheel-pieces are inclosed by cover-plates 23, which are flanged around the edges to fit around the sides of the wheel-pieces and are held in place by countersunk bolts which pass through angle-pieces 24, riveted inside the wheel-pieces. By this construction the wheel-pieces are held in rigid parallel alinement, and the members thereof are strongly braced against twisting or buckling.

The bolster is reinforced along its side edges by angle-bars riveted thereto on each side, and the sides are inclined upward at each end to meet the end cover-plates 29, which are formed as a part of the side-bearing castings 28. This gives to the bolster the character of a plate-truss of great strength and comparative lightness in weight. Beneath the center-plate the bolster is strengthened and stiffened

by cross-plates 25, formed from pressed-steel plates with flanges at top, bottom, and sides, the top and side flanges being riveted to the top and sides of the bolster, said plates being reinforced by the angle-bars 26, riveted thereto and to the bolster on the side opposite from the plate-flanges. Between these brace-plates 25 and beneath the hole for the king-bolt is a horizontal brace 27, intended to support the end of said bolt.

To allow for the side motion of the bolster relatively to the wheel-pieces and to return the bolster to mid-position after the deflecting force is removed, the bolster is equipped with abutments or follower-stops 30 and 33 at each side of the wheel-pieces, and helical springs 80 are positioned between followers 31 and 34, which engage the faces of said stops. The outside follower-stops 30 are formed by inward projections on the side-bearing castings 28, the inside follower-stops being steel castings riveted to the top of the bolster. The followers 31 are guided in chambered castings 32, riveted to the outside of the outer members of the wheel-pieces, the springs passing through said outer members of the wheel-pieces into engagement with said followers. The followers 34 are squared and pass through corresponding holes in the inside members of the wheel-pieces and through guides 35, formed on the brake-hanger bearings 36, which are riveted on the inward sides of the wheel-pieces. The horizontal channel-plates 7 are bent apart, so as to pass over and under these side-motion springs and act to stiffen the wheel-pieces where they are cut away to permit the passage therethrough of the springs and followers. The side-bearing castings 28 have their upper surfaces adapted to receive bearing-plates attached to the under side of the car-frame. To reinforce and stiffen the bolster at the points where the inside follower-stops and side bearings are secured thereto, I provide the flanged brace-plates 37, 38, and 39, the first two of which have end flanges riveted to the vertical sides of the bolster, and the rivets by which the side-bearing and follower-stop castings are secured to the bolster pass through the horizontal flanges at the top of said brace-plates. I also provide with this truck a novel arrangement of brake-rigging consisting of independent duplex-brake systems for each side of the truck. Each of these independent brake systems comprises a pair of brake-heads set between the wheels and supported by inverted-U-shaped shackles 41, which are hung in sockets formed by upwardly-inclined lips at 40 at each end of the castings 36, which constitute these hanger-bearings. The shackles are held in place in their bearings by means of blocks inserted between the lips 40 and held in place by bolts, as shown in Fig. 3. Coupled to each brake-head is a vertical lever 43, said le-

vers being coupled together by a connecting-bar 44. The upper end of one of these 5 brake-levers is coupled by connecting-rod 46 with a stationary eyepiece 45, formed on the hanger-bearing 36, and the free end of the other lever is coupled by a connecting-rod 47 to a horizontal equalizer-bar 48, which passes transversely across the truck over the center-plate, and consequently over or through the 10 depressed center sills of a car, where they rest upon the center-plate. This equalizer-bar is coupled at the center to the brake system, and from an inspection of Fig. 3 it will be seen that a pull to the left on the equalizer-bar will 15 act, through the brake-levers 43 and connections 44, to throw the brake-heads at each side of the truck to the right and left, and thereby set the brakes upon each of the four wheels, the brake system on one side of the truck acting 20 independently from that upon the other side.

Variations in the forms of the several parts which go to make up the truck and in the manner of assembling and building them up may 25 be made without departing from the spirit of my invention. Eyebars may be substituted for channels, and the pressed-steel members may have substituted therefor members of like form constructed of built-up parts, and I 30 do not, therefore, confine myself to the specific details of construction herein shown and described.

What I claim as my invention, and desire to secure by Letters Patent, is—

35 1. In a car-truck, the combination, with the wheel-pieces, of a bolster passing across below the wheel-pieces, and stirrups hung from the wheel-pieces and supporting the bolster.

2. In a car-truck, the combination, with the 40 wheel-pieces, of a bolster passing across below the wheel-pieces, springs at each side upon which the bolster rests, and stirrups supporting said springs, each stirrup comprising a horizontal carrier supported at each end by a 45 hanger depending from the wheel-pieces.

3. In a car-truck, the combination, with the 50 wheel-pieces, of a bolster passing across below the wheel-pieces, springs at each side upon which the bolster rests, longitudinal carriers for said springs beneath the wheel-pieces, and hangers supported by the wheel-pieces and 55 coupled to each end of the carriers, said hangers being hung to swing laterally upon their supports.

55 4. In a car-truck, the combination, with the wheel-pieces, of a bolster passing across below the wheel-pieces, springs at each side upon which the bolster rests, longitudinal carriers for said springs beneath the wheel-pieces, 60 hangers supported by the wheel-pieces on rocking bearings and coupled to each end of the carriers, and vertical guides depending from the wheel-pieces and engaging the sides of the bolster, whereby the bolster is permit-

ted to have vertical and lateral motions only 65 with respect to the wheel-pieces.

5. In a car-truck, the combination, with the wheel-pieces, of a bolster passing across below the wheel-pieces, springs at each side upon which the bolster rests, stirrups for the springs 70 hung from the wheel-pieces on rocking bearings, vertical guides depending from the wheel-pieces and engaging the sides of the bolster, whereby the bolster is restricted to vertical and lateral movements with respect 75 to the wheel-pieces, and side-motion springs between the bolster and wheel-pieces.

6. In a car-truck, the combination, with the wheel-pieces and a bolster, of bolster-stirrups comprising horizontal carriers, hangers coupled to each end of the carriers, a gib having a concave socket passed through an eye in each hanger, and supports for said gibs carried by the wheel-pieces.

7. In a car-truck, the combination, with the 85 wheel-pieces and a bolster, of bolster-stirrups comprising horizontal carriers, hangers having slotted eyes with convex ends, gibs having concave sockets on their lower edges passed through slotted eyes provided there- 90 for in the ends of the carriers and engaging the convex end of the lower hanger-eyes, gibs having concave sockets in their upper edges engaging the convex end of the upper hanger-eyes, and supports having transverse sockets 95 to receive said gibs carried by the wheel-pieces.

8. In a car-truck, the combination, with the wheel-pieces, of a bolster of inverted-U-shaped 100 cross-section passing across below the wheel-pieces, springs at each end between the vertical members of the bolster, and stirrups hung from the wheel-pieces and supporting said springs.

9. In a car-truck, the combination, with the 105 wheel-pieces, of a bolster of inverted-U-shaped cross-section, hung from the wheel-pieces, a center plate supported upon the bolster, and cross-braces between the vertical members of the bolster under the center plate.

10. In a car-truck, a combined bolster and 110 spring-beam of inverted-U-shaped cross-section, with the vertical members spaced apart to receive the bolster-springs between them.

11. In a car-truck, a combined bolster and 115 spring-beam formed from a steel plate bent lengthwise to the shape of an inverted U and having its vertical members spaced apart to receive the bolster-springs between them.

12. In a car-truck, a bolster of inverted-U- 120 shaped cross-section in combination with a center plate resting centrally upon the top of the bolster, and brace-plates between the vertical members of the bolster under the center plate.

13. A four-wheel car-truck comprising 125 wheel-pieces mounted upon springs resting upon the axle-boxes, a bolster passing across

- below the wheel-pieces between axles, stirrups hung from the wheel-pieces, and springs upon which the bolster rests supported by said stirrups.
14. A four - wheel car - truck comprising wheel-pieces composed of pairs of longitudinal members spaced apart, pedestals for the axle-boxes depending from the wheel-pieces and secured to both members of the wheel-piece pairs, springs between said members resting upon the axle-boxes, spring-caps secured between said members to receive said springs, a bolster passing across below the wheel - pieces between axles, springs upon which the bolster rests at each side, carriers for said springs, and hangers for said carriers hung from supports secured between the members of the wheel-piece pairs.
15. A car - truck frame comprising two wheel-pieces united at the ends by depressed cross-braces, in combination with a bolster passing across below the wheel-pieces between axles, said bolster resting in stirrups hung from the wheel-pieces between axles.
16. A car - truck frame comprising two wheel-pieces, each consisting of a pair of longitudinal members, and cross-braces uniting the wheel - pieces at their ends, said cross-braces having flat horizontal end portions passing across and fastened to both members of the wheel-piece pairs.
17. A car - truck frame comprising two wheel-pieces, each consisting of a pair of longitudinal members, cross-braces passing across below the level of the wheel-pieces and uniting the ends thereof, said braces being bent upward at each side and fastened to the under side of the wheel-piece pairs, and brackets fastened in the angles between the braces and the inner members of the wheel-pieces.
18. A car - truck frame comprising two wheel-pieces, each consisting of a pair of longitudinal members, cross-braces passing across below the level of the wheel-pieces and uniting the ends thereof, said braces being of inverted-U-shaped cross-section with their end portions bent upward and flattened out to engage the under side of both members of the wheel-piece pairs, and brackets fastened in the angles between the braces and the inner members of the wheel-pieces.
19. A car - truck frame comprising two wheel-pieces, and cross-braces uniting the ends thereof, said braces being of U-shaped cross-section and having their end portions flattened where they are united to the wheel-pieces with the inside flanges curved in to parallel the line of the wheel-pieces.
20. A car - truck frame comprising two wheel-pieces, each consisting of a pair of longitudinal members spaced apart and closed at the ends by flanged cover-plates.
21. A car - truck frame comprising two wheel-pieces, each consisting of a pair of lon-
- gitudinal members spaced apart with horizontal brace-plates fastened between. 65
22. A car - truck frame comprising two wheel-pieces, each consisting of a pair of channels with their flanged sides turned toward one another, and two horizontal channels with reversed flanges riveted between the wheel-piece channels. 70
23. A car - truck frame comprising two wheel-pieces, each consisting of a pair of channels with their flanged sides turned toward one another, spring-caps riveted between the wheel-piece channels near each end to receive axle-box springs, two horizontal channels with reversed flanges riveted between the wheel-piece channels and extending from spring-cap 80 to spring-cap, slots passing through the horizontal channels at each side of the center to permit bolster-hangers to pass therethrough, hanger-supports attached to the upper of said channels above the slots, slotted spacer-blocks 85 between channels below said supports, and bolster guide-brackets attached to the under channels and engaging the under flanges of the wheel-piece channels. 90
24. A car - truck comprising two wheel-pieces, each consisting of a pair of longitudinal members, spring-caps between said members above the axle-boxes, horizontal brace-plates between said members intermediate the spring-caps, a bolster passing across below the wheel-pieces, stirrups for the bolster having hangers passing up through slots provided therefor in the horizontal plates, and hanger-supports resting upon said plates. 95
25. In a car-truck, the combination, with the wheel-pieces, of a bolster passing across below the wheel-pieces, stirrups for the bolsters having hangers at each end supported by the wheel-pieces, abutments on the bolster at each side of the wheel-pieces and side-motion springs mounted on the wheel-pieces, between said abutments. 100
26. In a car-truck, the combination, with the wheel-pieces, of a bolster hung in stirrups from the wheel - pieces, side-motion springs 110 passing through the wheel-pieces above the bolster, followers engaging the ends of said springs, follower-guides mounted on the sides of the wheel-pieces, and follower-stops on the bolster at each side of the wheel-pieces. 115
27. In a car-truck, the combination, with the wheel-pieces comprising pairs of longitudinal members spaced apart, and having horizontal brace-plates between them, of a bolster hung in stirrups upon supports carried by said brace - plates, side - motion springs passing through the wheel-pieces between the brace-plates, spring-followers projecting from the wheel - pieces at each side, guides therefor mounted on the wheel-pieces, and follower-stops on the bolster at each side of the wheel-pieces. 120
28. In a car-truck, the combination with a

spring-beam of inverted-U-shaped cross-section, of a combined side bearing and cover-plate attached to each end of said beam.

29. In a car-truck, the combination, with
5 the wheel-pieces, of combined follower-guides
and brake-hanger supports attached to the in-
ward sides thereof.

In testimony whereof I have affixed my sig-
nature in presence of two witnesses.

WILLIAM F. KIESEL, JR.
